UNITED STATES PATENT OFFICE.

SAMUEL ORR, OF NASHVILLE, TENNESSEE.

AUTOMATICALLY-FOLDING STEP AND SEAT.

No. 841,565.

Specification of Letters Patent.

Patented Jan. 15, 1907.

Application filed July 13, 1906. Serial No. 326,123.

To all whom it may concern:

Be it known that I, SAMUEL ORR, a citizen of the United States, residing at Nashville, in the county of Davidson and State of Tennessee, have invented certain new and useful Improvements in Automatically-Folding Steps and Seats; and I do hereby declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to new and useful improvements in automatic folding steps and seats designed for use especially in stores to enable persons to reach objects at higher elevations than possible when standing upon a floor, and comprises a simple and efficient device of this character which when not in use will be held by a spring in a folded position and out of the way.

The invention relates to various details of construction, combinations, and arrangements of parts, as will be hereinafter more fully described and then specifically defined in the appended claims.

I illustrate my invention in the accompanying drawings, which, with the letters of reference marked thereon, form a part of this application, and in which—

Figure 1 is a side elevation of my invention, showing the seat or step open in solid lines and closed or folded in dotted lines. Fig. 2 is a front elevation of the step or seat folded. Fig. 3 is a sectional view on line 3 3 of Fig. 1, and Fig. 4 is a perspective view of the bracket-arm to which the seat or step is fastened.

Reference now being had to the details of the drawings by letter, A designates a strip which may represent any fixed object to which it may be desired to attach the device, and B is a bracket member having two arms B', which are spaced apart and flare outwardly. The upper surfaces of said arms near their ends are flattened and are adapted to form a support for the seat or step C.

D is a coiled spring the central portion of which is bent to form a loop D', supported by a screw E passing through the bracket-arm, and each arm D' of said spring is fastened to the under surface of the seat in such a manner that the seat will be normally held by the tension of the spring in an upright or closed

position, as shown in dotted lines in Fig. 1 of the drawings, said spring being of sufficient strength to hold the step or seat, as shown and described. The arms of the spring when 6c the step is lowered will contact with the inner edges of the arms of said bracket member adjacent to the flattened portions thereof and will serve to prevent lateral movement of the step, the under surface of the latter 65 resting upon the flattened portions of the bracket-arms when the step is in a horizontal position.

H is a support which is hinged at H' to the under surface of the step, and the lower portions thereof are formed into legs whereby the step may be supported in a horizontal position. An opening N is formed in the body portion of said support of sufficient size to receive the foot of a person and affording means whereby a person may place his or her foot therein as the first step. As pressure is applied thereto the seat or step proper will be drawn down to a horizontal position, whereby the person may ascend still higher. 80 Said opening also allows the bracket-arms to pass therethrough when the step is folded. The rear end of the step or seat C has a recess O adapted to allow the step to turn back without interference with the upper end of the 85 bracket member.

What I claim is—

1. In combination with a bracket member having outwardly-extending arms which are spaced apart, a spring supported by said 90 bracket member, portions of said spring forming arms, a step to which said arms are fastened, said arms of the spring adapted to contact with the arms of the bracket member to prevent lateral movement of the step, 95 and a hinged support fastened to the step, as set forth.

2. In combination with a bracket member having outwardly-flaring arms, a coiled spring having a central portion thereof bent to form a loop, a bolt secured to the bracket member, and upon which said loop is mounted, a step to which the arms of said spring are fastened, and a hinged support for the step, as set forth.

In testimony whereof I hereunto affix my signature in the presence of two witnesses.

SAMUEL ORR.
